UNITED STATES PATENT OFFICE.

ROBERT A. G. LORENZ, OF NEW YORK, N. Y.

CLAMP FOR STRINGS.

SPECIFICATION forming part of Letters Patent No. 375,710, dated December 27, 1887.

Application filed May 11, 1887. Serial No. 237,811. (No model.)

To all whom it may concern:

Be it known that I, ROBERT A. G. LORENZ, of the city, county, and State of New York, have invented certain new and useful Im- 5 provements in Clamps for Strings, &c., of which the following is a specification.

This invention has reference to an improved clamp for strings, &c., which is more especially adapted for connecting the tail-pieces of 10 stringed instruments to the body of the same; and the invention consists of a clamp for strings, &c., the hollow tapering body of which is provided with interior curved ribs at both sides, and with a tapering and serrated key 15 that clamps the strings wedged in between the sides of the clamp-body and the key.

In the accompanying drawings, Figure 1 represents the bottom view of the tail-piece of a strung instrument with my improved clamp 20 for the string by which the tail-piece is attached to the body of the instrument. Fig. 2 is a vertical longitudinal section of the tail-piece and clamp, drawn on a larger scale; and Fig. 3 is a detail horizontal section of the clamp detached from said tail-piece. 25

Similar letters of reference indicate corresponding parts.

Referring to the drawings, A represents the body of my improved clamp for strings, which 30 body is made in tapering shape and preferably provided with a convex bottom and flat top. The sides of the body A are provided with interior curved or thickened ribs, *a a*, which, in connection with a tapering key, B, that is inserted at the narrower end of the body A, serve to firmly clamp the string ends *d d* to the body of the clamp. The tapering key B is toothed or serrated at the sides, so as to bite 35 the strings and increase the clamping action

of the same on the body A. The key B is inserted with its thinner end at the narrower end of the body A, so that the greater the strain on the string the more the key is drawn into the body of the clamp and the tighter are the string ends clamped by the interior side 45 ribs, *a a*, of the body A and the tapering key.

My improved clamp is more especially intended for the gut strings by which the tail-piece of stringed instruments is attached to the body of the same, in which case the clamp 50 is seated in a recess at the under side of said tail end and the strings passed through connecting-holes of the same, as shown in Figs. 1 and 2. The clamp may, however, also be used for all other purposes for which an effective 55 string-clamp is required.

Having thus described my invention, I claim as new and desire to secure by Letters Patent—

The combination of a body having a re- 60 cess the width of which decreases from the ends toward a point between the ends, said recess serving to receive strings, one resting against each side edge of the recess, and of a tapered key having its edges serrated, the 65 teeth being inclined in the reverse of the direction of the string, and the smaller end of the key being at that end of the recess toward which the key is drawn by the strain in the string, substantially as set forth. 70

In testimony that I claim the foregoing as my invention I have signed my name in presence of two subscribing witnesses.

ROBERT A. G. LORENZ.
